UNITED STATES PATENT OFFICE.

JOSEPH MORITZ, OF NEW YORK, N. Y.

DESIGN FOR AN ADJUSTABLE LAMP-FIXTURE.

49,999.

Specification for Design.

Patented Dec. 5, 1916.

Application filed May 12, 1915. Serial No. 27,724. Term of patent 3½ years.

To all whom it may concern:

Be it known that I, JOSEPH MORITZ, a citizen of the United States, residing in the city, county, and State of New York, have invented a new, original, and ornamental Design for an Adjustable Lamp-Fixture, of which the following is a specification, reference being had to the accompanying drawing, forming part thereof.

The figures are respectively an elevation and a plan view of a lamp fixture showing my new design.

I claim:

The ornamental design for an adjustable lamp fixture as shown.

In testimony whereof I have hereunto set my hand in the presence of two subscribing witnesses.

JOSEPH MORITZ.

Witnesses:

GEORGE DU BOY,
ELMER G. WILLYOUNG.
